AEROSOL DEODORANT BOTTLE

Charles Arthur Howell, Ardsley-on-Hudson, N. Y., assignor to The Pharma-Craft Corporation, New York, N. Y., a corporation of Delaware

Application December 1, 1951, Serial No. 259,373

7 Claims. (Cl. 299—95)

This invention relates to aerosol bottles and more particularly to an aerosol bottle having a metering discharge valve for discharging the fluid contents of the bottle in measured puffs of mist or spray.

According to the invention, an aerosol bottle is provided having a special valve arrangement which is adapted to discharge only a limited quantity of the fluid contents of the bottle upon each actuation of the valve. The special valve arrangement according to the invention comprises a valve housing which provides a fluid measuring chamber, a valve stem having a shank accessible for manual operation from the outside of the bottle, a valve shank sleeve which is connected to the housing in such manner that a resilient gasket serves not only to form an effective seal between the sleeve and housing but also as a valve seat for an outlet valve on the stem, said sleeve also providing an expansion chamber in which is a discharge orifice. The sleeve which is connected to the valve housing is so designed as to accommodate a gasket to effectively seal the juncture between the valve parts and the metallic walls of the bottle to prevent escape of the bottle contents from the main body of fluid in the bottle and a cap is provided which is so designed as to accommodate a gasket to seal the juncture between the cap and valve stem sleeve and also to provide protection against accidental displacement of the valve stem. The valve housing is also provided with an inlet port and a valve openable and closable in response to movement of the stem.

The bottle is particularly useful for dispensing a spray deodorant; that is, deodorant carried in a liquefied aerosol propellant such as Freon. Such aerosol spray deodorant bottles are on the market having non-metering valves and it will be understood that this invention relates primarily to the construction of the valve which, upon actuation, meters the fluid discharged from the bottle. Although the aerosol bottle is herein described as an aerosol deodorant bottle it will be understood that it lends itself for use with other agents which may be dispersed as an aerosol by aerosol fluid propellants such as Freon and the like.

The invention will be understood by reference to the accompanying drawings showing a preferred embodiment, in which:

Fig. 1 is a top plan view of the aerosol deodorant bottle embodying the invention;

Fig. 2 is a view in elevation and partly in section of the bottle shown in Fig. 1;

Fig. 3 is a view in section and to larger scale of the upper end of the bottle showing the valve and related parts; the valve stem and valves being in normal position;

Fig. 4 is a view similar to Fig. 3 showing the valve stem pressed down;

Fig. 5 is a view on line 5—5 of Fig. 4; and

Fig. 6 is a view on line 6—6 of Fig. 3.

By reference to the drawings, in which like reference characters indicate like parts throughout the several figures, it will be seen that the illustrated embodiment comprises a bottle having a cylindrical side wall 20, a bottom closure 21, a top wall 22, all made of metal, a cover cap 23, a metering valve 24, and a tube 25 extending from the valve to the bottom of the main body portion of the bottle.

As is well known in the art, the fluid propellant, together with the deodorant agent in the bottle, is under pressure of the fluid propellant.

2

The top wall 22 of the bottle has a centrally located upwardly extending neck 26 comprising a cylindrical side wall 27 having an annular inturned flange 28 providing a central opening 29; this part of the bottle being of standard design now available in the market. However, the cylindrical upstanding wall 27 forming the neck portion 26 will not have been crimped as shown at 30; this crimping operation not being performed until after the valve parts have been assembled and inserted in the neck portion 26 of the bottle.

The valve mechanism comprises generally a valve housing 31, a valve stem sleeve 32, a valve stem 33 having a valve disc 39, a cover cap 23, all of which are molded parts which may readily and economically be made of moldable plastic material, or of metal, or other suitable material, a valve shank gasket 34, a valve sleeve gasket 35, and a valve housing gasket 36; all of which are rubber ring gaskets, preferably synthetic rubber of the "Neoprene" type; a metallic helical compression spring 37, and a ball valve 38.

The valve housing 31 is generally cylindrical having side wall 40 terminating at its upper end in an annular shoulder 41 which extends outwardly from the wall and has an upper flat annular surface 42. The bottom wall 43 of the housing has a depending centrally bored boss 44 providing an inlet port into the chamber defined by the housing; it being noted that the inner surface of the bottom wall is tapered slightly; thus forming a valve seat 45 at the periphery of the central inlet passageway 46. The central bore 47 of the housing is widened at its upper end to provide an annular shelf 48 upon which rests the ring gasket 36; this upper widened bore receiving the telescoping lower end 49 of the valve stem sleeve 32, which rests upon gasket 36. The upper end of tube 25, which is made of plastic, fits over the depending boss 44 of the valve housing and this tube extends to the bottom of the bottle as shown in Fig. 2. Thus a passageway is provided from the body of fluid 50 through the inlet port 51 of the valve housing into the measuring chamber 52 provided by the valve housing.

The valve shank 53 extends through ring gasket 34 and through an aperture in the top wall of cap 23, it being noted that the top wall 54 of the cap has a spherically shaped depression 55. The shank 53 is vertically slidable in the gasket 34 and it will be noted that in its normal position shown in Fig. 3, the top of the shank lies flush with the top of the cap. The depression 55 provides an indentation to accommodate a finger when the valve stem is manually pressed down against the force of spring 37. The gasket 34 provides an effective seal between the valve stem sleeve 32 and the cap 23.

The valve stem 33 is reduced in size at the lower end of the sleeve, providing a reduced shank portion 56 and at the end of the shank portion 56 is an enlarged annular shoulder portion providing a valve seating portion 57 at its upper annular surface and a spring seating portion 58 at its lower surface. Depending from the shoulder portion is a centrally located boss 59 which serves as a post on which to mount the helical compression spring 37 and also as a post to engage the ball 38 and press the ball onto seat 45 to close passageway 46 when the valve stem is pressed down as shown in Fig. 4.

The reduced shank portion 56 has a vertical groove 60 in its peripheral surface which terminates at its lower end short of the valve seating portion 57 of the valve disc 39. It will be observed that the ring gasket at its central opening hugs the reduced shank portion 56 and when the valve stem is up as shown in Fig. 3, communication between the measuring chamber 52 (provided by the housing 31) and the expansion chamber 62 (provided by sleeve 32) is closed off. When the valve stem is pressed down as shown in Fig. 4, the valve disc 39 is unseated and the restricted passageway 60 provides communication between chambers 52 and 62, through the outlet port provided through the central opening of the gasket 36.

The valve sleeve 32 intermediate its upper and lower ends has an annular shoulder or boss 63 the upper surface of which engages the gasket 35 and the lower surface of which engages the upper surface 42 of the

valve housing 31; the gasket 35 providing an effective seal between the inturned flange 28 and the shoulder 63 to prevent leakage to the atmosphere of vapor or contents from the main body 50 of liquid in the bottle.

The cap 23 is cup-shaped and its top wall has a bore 65 into which the upper end of sleeve 32 telescopically fits, it being noted that the sleeve has a keyway 66 to receive a key 67 molded in the bore 65. When the cap 23 is press fitted onto the sleeve the key rests in the keyway. The cap has an outwardly flaring discharge passage 68, the inner end of which registers with a discharge orifice 69 in the sleeve wall, when the cap is in place with the key 67 in the keyway 66.

The valve housing and sleeve are held in position by a rolled crimp 30. This rolled crimp is made in the metal wall 27 after the valve assembly is put in place in the neck, it being noted that the crimp squeezes the shoulder 41 of the housing 31 against annular boss 63 of the sleeve which in turn squeezes against the gasket 35, thus to hold the valve firmly in place.

The bottle operates as a metering aerosol bottle as follows: When the valve stem 33 is up, that is in normal position as shown in Fig. 3, the vapor pressure on the surface of fluid 50 in the bottle forces fluid up through tube 25, through port 51 past ball 38 into measuring chamber 52, until pressure equilibrium between the body of the bottle and the measuring chamber is reached. Only a limited amount of liquid flows into the measuring chamber because flow out of this chamber is prevented by valve disc 39 which is then closed and acts as a check valve because spring 37 urges the stem to normal position and the seating portion 57 of the disc 39 against gasket 36. The vapor pressure in the bottle is sufficient to overcome the weight of floating ball valve 38 to permit the fluid to flow into chamber 52. To discharge fluid from the bottle, the valve stem 33 is pressed down by finger pressure on top of the stem against the force of spring 37. The post 59 engages the ball 38 and forces it to seat to close port 51 and valve disc 39 is unseated so that restricted passageway 60 provides communication between chambers 52 and 62, as shown in Fig. 4. The stem is designed so that ball 38 seats just in advance of opening passageway 60. The fluid that is trapped in measuring chamber 52 then passes through passageway 60 and expands into expansion chamber 62 and is discharged through discharge orifice 69 and passes through the outwardly flared discharge tunnel 68 as a measured puff of mist. No more fluid is discharged than that trapped in the measuring chamber 52 because ball valve 38 is seated and prevents this. To obtain another puff of mist or spray from the bottle the valve stem 33 must be released so that it assumes normal position so as to permit an additional supply of fluid from the bottle to enter the measuring chamber. Then the valve stem may again be pressed down to repeat the cycle, each actuation of the valve discharging a measured amount of fluid from discharge orifice 69 as a puff of mist.

The terms and expressions which have been employed herein are used as terms of description and not of limitation, and there is no intention in the use of such terms and expressions of excluding any equivalent of the features shown and described or portions thereof, but it is recognized that various modifications are possible within the scope of invention claimed.

What is claimed is:

1. A metering aerosol bottle which comprises a main body portion holding a main body of aerosol fluid propellant, said body portion having a top wall, a hollow neck portion extending upwardly from the top wall of said body portion and having an inturned flange providing a central opening, a valve housing providing a measuring chamber mounted in said neck having a side wall and a bottom wall, said bottom wall having a port and providing a valve seat, a conduit for the passage of fluid from said main body of fluid to said port, a valve stem sleeve having its upper end protruding through said central opening and its lower end engaging said housing and providing an expansion chamber, a gasket surrounding said sleeve under said inturned flange and providing a leakproof seal between said sleeve and flange, and having a discharge orifice, a valve stem reciprocatable in said sleeve having a stem shank accessible for manual operation from outside

5 said bottle, a gasket surrounding said stem and providing a seal between said sleeve and stem, an outlet valve having a disc positioned in said housing, means providing a seat for said valve disc, spring means 10 urging said valve disc to seat on said seat, said stem having a restricted passageway which is closed by said valve when seated and which is opened to provide communication between said measuring and expansion chambers when unseated, an inlet valve in said housing, said outlet valve being unseated and said inlet valve being seated in response to inward movement of said stem, said outlet valve being seated and said inlet valve unseated in response to outward movement of said stem by the force of said spring means.

2. A metering aerosol bottle which comprises a main body portion holding a main body of aerosol fluid propellant, said body portion having a top wall, a hollow neck portion extending upwardly from the top wall of said body portion and having an inturned flange providing a central opening, a valve housing providing a measuring chamber mounted in said neck having a cylindrical side wall and a bottom wall, said bottom wall having a port and providing a valve seat, a conduit connecting said port with said main body of fluid, a valve stem sleeve having its upper end protruding through said central opening and its lower end engaging said housing and having a discharge orifice, said sleeve providing an expansion chamber, a valve stem reciprocatable in said sleeve having a stem shank accessible for manual operation from outside said bottle, an outlet valve having a seating portion, a resilient ring gasket clamped by said sleeve and housing and providing a resilient seat for said seating portion, a compression spring urging said outlet valve seating portion to seat on said resilient seat, said stem having a restricted passageway which is closed by said outlet valve when seated and which is opened to provide communication between said measuring and expansion chambers when unseated, a ball valve in said housing, said outlet valve being unseated and said ball valve being seated in response to inward movement of said stem, said outlet valve being seated and said ball valve unseated in response to outward movement of said stem by the force of said spring, and a gasket sealing the juncture of said sleeve and neck portion preventing leakage of the contents from said bottle.

3. An aerosol bottle which comprises a main body portion, a top wall, a hollow neck extending upwardly from said top wall and having an inturned flange defining a central opening, said main body portion being adapted for holding a liquid aerosol propellant, a hollow sleeve having a discharge orifice and having an outwardly extending annular boss, said sleeve extending through said central opening and providing an expansion chamber, a valve housing open at its upper end and having an outwardly extending annular shoulder and having a bottom wall in which is an inlet port, a conduit connected to and extending from said inlet port and terminating near the bottom of said body portion, said housing providing a measuring chamber, said annular boss on said sleeve and said annular shoulder on said housing being disposed within said neck, a sealing gasket between said boss and inturned flange surrounding said sleeve and clamped against said inturned flange, means defining an outlet port from said measuring chamber into said expansion chamber, an outlet valve movable in said housing for opening and closing said outlet port, an inlet valve in said housing for opening and closing said inlet port, a valve stem shank reciprocatable in said sleeve and accessible from the outside of said bottle for manual operation, said outlet valve opening said outlet port and said inlet valve closing said inlet port in response to inward movement of said shank and said outlet valve closing said outlet port and opening said inlet port in response to outward movement of said shank, and a flexible gasket surrounding said stem at the outer end of said sleeve providing a seal between said sleeve and stem.

4. An aerosol bottle which comprises a main body portion, a top wall, a hollow neck extending upwardly from said top wall and having an inturned flange defining a central opening, said main body portion being adapted for holding a liquid aerosol propellant, a hollow sleeve having a discharge orifice and having an outwardly extending annular boss, said sleeve pro-

truding through said central opening and providing an expansion chamber, a valve housing open at its upper end and having an outwardly extending annular shoulder and having a bottom wall in which is an inlet port, a conduit extending from said inlet port and terminating near the bottom of said body portion, said housing providing a measuring chamber, said annular boss on said sleeve and said annular shoulder on said housing being disposed within said neck and clamped against said inturned flange, means defining an outlet port from said measuring chamber into said expansion chamber, an outlet valve having a disc movable in said housing for opening and closing said outlet port, an inlet valve in said housing for opening and closing said inlet port, a valve stem shank secured to said disc reciprocatable in said sleeve and accessible from the outside of said bottle for manual operation, said outlet valve opening said outlet port and said inlet valve closing said inlet port in response to inward movement of said shank and said outlet valve closing said outlet port and opening said inlet port in response to outward movement of said shank, a cap fitted on said protruding sleeve having an aperture through which said shank extends and having a spray tunnel in registry with said discharge orifice in said sleeve.

5. An aerosol bottle having a measuring chamber and a valve mechanism adapted to discharge the aerosol fluid propellant through a discharge orifice in measured individual puffs of mist which comprises a bottle holding a main body of aerosol fluid propellant and having an upstanding hollow neck with an inturned flange defining a central opening, a valve housing providing a measuring chamber in said neck having an outlet opening in its upper end and an inlet port in its bottom end, a conduit extending from said inlet port and terminating near the bottom of said bottle, an outwardly extending annular shoulder on said housing, a resilient gasket at said outlet opening providing an outlet port from said measuring chamber, a valve stem sleeve having its upper end extending through the central opening defined by said inturned flange and having a discharge orifice and having an outwardly extending annular boss, a ring gasket engaging said annular boss, said annular boss and ring gasket being clamped against said inturned flange by said annular shoulder, a valve stem having a shank reciprocatable in said sleeve and accessible from the outside of said bottle for manual operation and having a valve disc in said housing for opening and closing said outlet port, a floating valve in said housing for opening and closing said inlet port, a compression spring in said housing urging said valve disc to normal closed position, said valve disc opening said outlet port and said floating valve closing said inlet port in response to inward movement of said shank against the force of said spring and said valve disc closing said outlet port in response to outward movement of said spring and said floating valve opening under the force of fluid pressure from said main body of fluid when said valve disc is moved to closed position.

6. An aerosol bottle adapted to discharge liquid aerosol propellant as individual measured puffs of mist which comprises a metallic bottle portion, a metallic hollow neck having an inturned flange providing a central opening, a valve housing in said hollow neck providing a measuring chamber and having an annular shoulder disposed in its interior surface, a resilient outlet port gasket resting on said shoulder and providing an outlet

port from said measuring chamber, means defining an inlet port into said measuring chamber, a conduit extending from said inlet port and terminating near the bottom of said bottle, a hollow valve stem sleeve engaging and clamping said outlet port gasket against said shoulder and having its upper end protruding through said central opening and having a discharge orifice in said upper end, said sleeve and housing having outwardly extending flanges clamped within said neck, a valve stem gasket resting on the outer end of said sleeve, a cap press-fitted on said sleeve and having a central opening, a valve stem having a shank reciprocatable in said sleeve and the central opening of said cap, a spray tunnel in said cap registering with said discharge orifice, an outlet valve on said stem having a seating portion for opening and closing the outlet port of said measuring chamber in response to reciprocal movement of said shank, a valve in said housing for opening and closing the inlet port into said measuring chamber in response to reciprocal movement of said shank, and a yieldable spring means engaging said stem urging said seating portion against said gasket at the outlet port of said measuring chamber.

7. An aerosol bottle adapted to discharge liquid aerosol propellant as individual measured puffs of mist which comprises a metallic bottle portion, a metallic hollow neck having an inturned flange providing a central opening, a valve housing in said hollow neck providing a measuring chamber and having an annular shoulder disposed in its interior surface, a resilient outlet port gasket resting on said shoulder and providing an outlet port from said measuring chamber, said housing having a bottom wall defining an inlet port into said measuring chamber, a conduit extending from said inlet port to near the bottom of said body portion, a hollow valve stem sleeve engaging and clamping said outlet port gasket against said shoulder and having its upper end protruding through said central opening and having a discharge orifice in said upper end, said sleeve and housing having outwardly extending flanges clamped within said neck, a valve stem gasket resting on the outer end of said sleeve, a cap press-fitted on said sleeve and having a central opening, a valve stem having a shank reciprocatable in said sleeve and the central opening of said cap, a spray tunnel in said cap registering with said discharge orifice, a valve disc on said stem for opening and closing the outlet port of said measuring chamber in response to reciprocal movement of said shank, a floating valve in said housing for opening and closing the inlet port into said measuring chamber in response to reciprocal movement of said shank, and a helical compression spring engaging said stem and the bottom wall of said housing around said inlet port and urging said valve disc against said gasket at the outlet port of said measuring chamber.
